UNITED STATES PATENT OFFICE.

WESLEY J. BALKWILL, OF ROCHESTER, NEW YORK, ASSIGNEE TO MULTIPORT COMPANY, OF ROCHESTER, NEW YORK, A CORPORATION OF NEW YORK.

STAMP-AFFIXER.

1,240,808.

Specification of Letters Patent. Patented Sept. 25, 1917.

Application filed September 27, 1915. Serial No. 52,885.

To all whom it may concern:

Be it known that I, WESLEY J. BALKWILL, of Rochester, in the county of Monroe and State of New York, have invented certain new and useful Improvements in Stamp-Affixers; and I do hereby declare the following to be a full, clear, and exact description of the same, reference being had to the accompanying drawings, forming a part of this specification, and to the reference-numerals marked thereon.

My present invention relates to machines adapted to be employed for affixing stamps or labels to pieces of mail matter or other articles in which successive stamps or labels are fed out of the machine, and it has for its object to provide an improved arrangement of counter or register actuating mechanism whereby an accurate count of the number of stamps or labels discharged may be obtained.

A further object of the invention is to provide improved means for increasing the frictional contact between each of a pair of frictional rollers and a stamp strip passing between the rollers. To these and other ends the invention consists in certain improvements and combinations of parts, all as will be hereinafter more fully described, the novel features being pointed out in the claims at the end of the specification.

In the drawings:

Figure 1 is an enlarged view shown partly in section, embodying the features of the invention;

Fig. 2 is a rear face view of the guide through which the stamps or labels are fed;

Fig. 3 is a sectional view through the stamp case, showing the guideway removed to expose the side thereof which faces the feeding mechanism;

Fig. 4 is a horizontal sectional view taken on line *a—a* of Fig. 2;

Fig. 5 is a detail side view of the clamping member through which stamps or labels are fed, and

Fig. 6 is a horizontal view of the same.

Similar reference numerals through the several views indicate the same parts.

In stamp or label affixing machines where the stamps or labels are to be delivered successively from a continuous strip which is supplied to the machine in the form of a

roll, it is very necessary to keep an accurate record of the number of stamps and labels used and especially of postage stamps, because of their monetary value. The device by which such a record is obtained must be incapable of having its counter or registering mechanism operated except when in proper engagement to be actuated directly by the stamp or label strip as the same is fed forwardly by the feeding mechanism.

The present embodiment of the invention is adapted to accomplish this result and the machine is constructed in such a way that in the event of any inaccuracy occurring in the operation of the stamp or label feeding mechanism, whereby the strips are not advanced, no movement will be imparted to the counter mechanism and consequently no record made.

In illustrating the features of the present invention I have shown them applied to a stamp affixing machine of commercial form comprising a base 1 supporting a frame 2 in which is guided a vertically reciprocating shaft or plunger 3 carrying an affixing head 4.

At one side of the machine the frame 2 is open and removably fitted in said opening is a circular stamp or label case 5 containing a roll of stamps or labels 6 shown passing downwardly through the guideway consisting of the backing 7 and the removable clamping member 8, terminating in laterally curved portions 9 and 10 respectively, which are adapted to direct the free end of the stamp strip over the cutting edge 11 and into the path of the affixing head or member 4. The stamp strip is fed forwardly and successively by a suitable feeding mechanism carried on the shaft or plunger 3 and in the present instance comprises feeding fingers 12, the pointed ends of which, are adapted to engage the perforations between the successive stamps during their downward movement.

A counter mechanism 13 is indicated, which may be of any desired construction and arranged on the frame of the machine, but is preferably mounted on the detachable stamp case, the window portion or front 14 projecting through an aperture in the outer wall 15 of the casing, so that the numeral wheels of the counter may be con-

veniently viewed and their operation observed. The counter is preferably connected to a yoke 16 which is secured to the sides of the casing in the manner shown in Fig. 4.

5 The construction of the mechanism of the counter has been omitted, but it will be understood that the numeral wheels and devices for operating them are driven by a central shaft 17 which carries a pinion 18 meshing with a gear wheel 19 preferably journaled in one side of the casing, as shown in Fig. 4. The gear wheel 19 is adapted to be driven by a pinion 20 preferably secured on the end of a friction roller 21 journaled in the sides of the casing supporting the stamp roll. The friction roller 21 is so disposed as to extend through an aperture formed between the bottom of the cylindrical casing 5 and the top of the backing 7 as shown in Fig. 1 and is arranged to contact with the stamp strip passing through the guideway. This roller and the gear wheel 19 and pinions 18 and 20 are proportioned so that the mechanism of the counter 13 will be actuated once for each complete stamp fed through the guideway.

10 The clamping or detention member for preventing the withdrawal of the stamp strip by a force applied to its free end comprises means for mounting said member whereby it may be conveniently removed to facilitate the insertion of the stamp strip. The removable clamping member is disposed in front of the guideway 7 between the side walls 22 of the casing and comprises the plate 23 in which is formed an aperture 24 through which the feeding fingers 12 project, said plate having at its lower end the curved portion 10 coöperating with the curved part 9 of the backing as previously stated to guide the stamp strip across the cutting edge 11. At its upper end the top of the plate is bent forming the somewhat angular portion 25 providing fulcrum points 26 around which the clamping member rotates in the event its lower end is displaced relatively to the guide, as occurs when the free end of the stamp strip is drawn forwardly. The clamping member also comprises the lateral extensions 27 lying within the walls 22 to which they are pivoted and on which they have a relative sliding movement. This form of construction is afforded by reason of the elongated slots 28 accommodating the securing devices which enter apertures in the walls 22. The securing devices in the present instance consist of the laterally projecting horizontal ends 29 of a U-shaped member 30 attached to the clamping member by means of the ears 31 at the bottom thereof. In forming the parts just described, I have shown on the U-shaped member 30 outwardly curving loops 32 which extend beyond the edges of the side walls 22 and lateral extensions 27 to afford means

whereby the member may be conveniently gripped by the operator's fingers, so that he may simultaneously retract the projecting ends 29 and thus release the clamping member and remove it from the guideway.

15 The clamping member is caused to normally exert a slight frictional contact with the stamp strip and to this end there is applied to each side of the member a spring 33 held in position at one end by an upwardly standing lug 34 on the lateral extension 27 and having an end 35 secured beneath a lug 36 and another end 37 provided with an eye 38 wrapped around and adapted to bear against the horizontal end 29 of the U-shaped member 30.

20 By this arrangement the opposite extremities of the spring are adapted to yieldingly hold the clamping member in engagement with the stamp strip upon the backing 7 of the guideway. The clamping member being thus yieldingly held will, when displaced at its lower end, rotate about the points 26 by reason of the movement afforded by the slots 28 and any additional tension under such circumstances is imparted to the spring 33 so that the greater the strain applied to the lower end of the stamp strip the greater becomes the clamping action between the upper end of the plate 23 and the backing 7 of the guideway. In order to insure a driving contact between the roller 21 and the stamp strip, the latter is held in contact with the former by means of a spring pressed frictional roller 39 mounted slightly above and over the roller 21, thereby deflecting the stamp strip and increasing the frictional contact between each of the rollers and the strip as clearly shown in Fig. 1.

25 The friction roller 39 is provided with projecting ends 40 from which extend reduced bearings 41 adapted to be positioned in elongated apertures 42 and 43 at the top of the lateral extensions 27. The aperture 43 is enlarged as shown in Fig. 5 in order to permit of the insertion and removal of the frictional roller from the clamping member by slipping one of the ends 40 into the enlarged aperture so that the opposite reduced bearing 41 may be positioned in or removed from the aperture 42. As a means for holding the friction roller 39 in a yielding and driving engagement with the stamp strip, I preferably continue the end 37 of the spring 33 upwardly from the eye 38 through a holding lug 44 on the angular portion of the clamping member to form a spring 45 having its free end bearing against the projecting end 40 of the roller as clearly shown in Figs. 1 and 2.

30 A floating shear or knife member 46 movably mounted on the affixing head 4 is adapted to coöperate with the cutting edge 11 on the downward stroke of the plunger to

sever the individual stamps from the strip as the same are fed forwardly by the fingers 12.

I claim as my invention:

- 5 1. In a stamp affixer, the combination with a stamp guideway comprising a backing and a removable clamping member, of an affixing member and devices for feeding a stamp strip through said guideway, and a 10 yieldingly mounted frictional roller in engagement with the stamp strip for the purpose of deflecting the same with respect to the guideway.
- 15 2. In a stamp affixer, the combination with a stamp guideway comprising a backing and a removable clamping member, of an affixing member and devices for feeding a stamp strip through said guideway, a friction roller mounted on one side of the stamp 20 strip in engagement therewith, and a yieldingly mounted frictional roller on the opposite side of the stamp strip arranged slightly above the first mentioned roller whereby the strip is deflected with respect 25 to the first mentioned roller to increase the frictional contact between the rollers and the strip.
- 30 3. In a stamp affixer, the combination with a stamp guideway comprising a backing and a removable clamping member, of an affixing member and devices for feeding a stamp

strip through said guideway, of a counter mechanism, a friction roller engaging one side of the stamp strip, gear wheels connecting the roller with the counter mechanism 35 for operating the same, and a yieldingly mounted frictional roller on the opposite side of the stamp strip positioned slightly above the first mentioned roller for the purpose of deflecting the strip to increase the 40 frictional contact between each of said rollers and said strip.

4. In a stamp affixer, the combination with a stamp guideway comprising a backing and a movable clamping member having spaced lateral extensions thereon extending above said guideway each provided with an aperture, an affixing member, and devices for feeding a stamp strip through said guideway, a friction roller engaging one side of the stamp strip above the guideway, and a friction roller on the opposite side of the stamp strip yieldingly mounted in the apertures and adapted to deflect the strip with 50 respect to the first mentioned roller for the 55 purpose of increasing the frictional contact between said strip and said rollers.

WESLEY J. BALKWILL.
